W. Schonmuth's wip'd
design for buckle, Springfield, Mass.

3783

PATENTED DEO 7 1869

Fig. I

Fig. II

Reg. June 23/69

United States Patent Office.

D. SCHOONMAKER, OF SPRINGFIELD, MASSACHUSETTS.

Design No. 3,783, dated December 7, 1869.

DESIGN FOR A HARNESS-BUCKLE.

The Schedule referred to in these Letters Patent and making part of the same.

To all whom it may concern:

Be it known that I, D. SCHOONMAKER, of Springfield, Hampden county, State of Massachusetts, have invented a new and improved Design for Buckles for Harness; and I do hereby declare that the following is a full and clear description thereof, reference being had to the accompanying drawings, and to the letters of reference marked thereon.

In the drawings—

Figure I shows a side view, and

Figure II, a plan view of my buckle.

Figure III is a diagram of a section of a part of the same.

This design consists in forming the front part of the buckle, at A, flat, and sharp-edged in front, while the rear edge of the part A, where the strap presses against,

is rounded, at B. The section of this part A would, therefore, form an isosceles triangle, with convex sides, such as is shown in Fig. III.

The side-pieces of this buckle-frame are not shaped as the front piece A, but are rounded as usual.

The buckle so formed presents a neat appearance, and allows the strap to be folded closer, and more neatly under it at the end.

Now, having described my invention,
What I claim as new, and desire to secure by Letters Patent, is—

The design for buckle, herein shown and set forth.

D. SCHOONMAKER.
